MICROPHONE PLUG

Everette M. Foster, Cedar Rapids, Iowa, assignor
to The Turner Company, Cedar Rapids, Iowa,
a corporation of Iowa

Original application April 17, 1935, Serial No.
16,786, now Patent No. 2,062,125. Divided and
this application November 23, 1936, Serial No.
112,422

6 Claims. (Cl. 179—189)

This invention relates to microphone structures and support stands and has particular relation to means for locking the microphone to the support stand. This application is a division of my

5 Patent No. 2,062,125, issued October 15, 1936.

It is the usual practice to mount a microphone unit on a standard by means of a removable jack connection but it has been found that where the microphone and stand are placed in public places 10 such as theater lobbies, on stages, and the like, the microphones are oftentimes stolen. It is just a matter of a moment for a thief to jerk the microphone off its stand, conceal it about his person and walk away. In fact, the microphone may 15 be removed from the stand of the prior art in a single motion while the thief is walking past the microphone.

It is therefore a primary object of my invention to provide a microphone support stand which 20 will deter thieves from stealing a microphone from a stand.

Another object of my invention is to provide a means for locking a microphone to a stand in such a manner that a thief in attempting to remove a microphone would make a sufficient number of motions and take sufficient time in removing the microphone that he would be observed, and yet permit an authorized individual to remove the microphone without undue loss of time.

30 Another object of my invention is to provide positive locking means for locking the microphone to a support standard.

A feature or advantage of my invention is that positive electrical connections are provided which 35 prevent "rattling" in the pick up circuit. Furthermore, a connection of this kind is not likely to be jerked apart accidentally.

Other and further features and objects of my invention will be more apparent to those skilled 40 in the art upon a consideration of the accompanying drawing and following specification, wherein is disclosed several exemplary embodiments of the invention, with the understanding, however, that such changes may be made there- 45 in as fall within the scope of the appended claims without departing from the spirit of the invention.

In said drawing:

50 Figure 1 is a view in elevation of a microphone and plug connection embodying my invention.

Figure 2 is a view in section of the end of the standard adapted to receive the microphone and plug connection shown in Figure 1.

55 Figure 3 is a partial view in elevation of an-

other plug connection for a microphone constructed according to my invention.

Figure 4 is a view in section of the end of a microphone support standard constructed according to another embodiment of my invention 5 and adapted to engage the plug of Figure 3.

Figure 5 is a partial view in elevation of the end of the standard shown in Figure 4.

Figure 6 is a partial view, partly in elevation and partly in section, of a microphone plug con- 10 structed according to another embodiment of my invention.

Figure 7 is a view, partly in section and partly in elevation, of the end of a standard which will 15 engage the plug shown in Figure 6 as constructed according to another embodiment of my invention; and

Figure 8 is a view in section taken along the line 8—8 of Figure 6.

Referring now to the drawing:

There is shown at 10 generally a microphone such as is used with radio broadcasting systems, public address systems and the like. These microphones ordinarily employ the plug and jack connections shown in Figures 1 and 2 including in the plug a barrel 11 and insulated button 12 and utilizing the jack portion which consists of the tubular standard 13 threaded at its upper inner wall to receive a thimble 14. The thimble 14 has a bore 16 leading longitudinally there- 20 through of such diameter as to receive the barrel 11 of the plug. The thimble 14 has a down- 25 wardly extending strap 17 which affords means for mounting a spring clip 18. The clip 18 is provided with a latch 19 to engage the post 12 of the plug and with a binding post 21 to furnish 30 means for electrically connecting a lead to the clip. The cylindrical standard, the thimble 14, and the barrel of the plug form the other elec- 35 trical conductor for the circuit.

One means of locking the plug within the thimble 14 is to employ the thread 23 formed at the base of the barrel 11 of the plug and provides the thimble 14 with a female thread 24 to engage the male thread 23 in connecting the 40 microphone to the standard. The plug is inserted in the thimble and then rotated several times as to cause the thread 23 to be threaded into the thread 24. It is apparent that a thief, in order to remove the microphone, must rotate 45 the microphone several times. Ordinarily, the thief would not realize that the microphone could be removed in this manner and if he does take the time to remove the microphone, his motion in doing so would attract the attention of at- 50 55

tendants and permit them to stop the thief before he had completely removed the microphone.

In some instances where the microphone is not well watched, a device, such as shown in Figures 3, 4, and 5, may be employed. The plug 11a is provided with a recess 15 and a set screw 26 is threaded to the wall of the thimble 14a and is so located that when the plug has been threaded into complete engagement, the recess 15 of the plug coincides with the point of the set screw and the set screw may be tightened down to engage the recess to prevent rotation of the plug. The head 26a of the set screw 26 is of peculiar shape, as for instance the triangular shape shown, so that a special wrench is needed to tighten and loosen the set screw and the head of the set screw is surrounded with a boss 28 which prevents the set screw from being rotated by means of a pliers or the like.

20 In some extreme cases a device, such as shown in Figures 6, 7 and 8, may be employed. In this device the microphone face is provided with a lug 31 having a slotted recess 32 in the under side of the projecting portion of the lug. A similar lug 33 is provided as a part of the thimble 14b. The lug 33 is provided with a vertical bore at its outer end which is coaxial with the slot 32 of lug 31 and the cylinder 34 of an ordinary tumbler lock is placed in the vertical bore of the lug 33. The rotating portion of the cylinder is provided with a shaft 36 and a lug 37, and in locking the microphone to the standard, the key 38 is rotated to the unlocked position and the plug inserted in the standard. At the same time that the plug is finally inserted into the standard, the cam 37 slides into the slotted recess 32. The key 38 is then rotated 90° to cause the cam to engage in an offset portion 32a of the recess 32 to lock the cam in the recess. The key is then removed and in this way the microphone is locked to the standard in such a way that it cannot be removed. In this manner, the microphone may be positively locked to the standard and cannot be removed by any unauthorized individual.

45 It is apparent that in one form of my invention I have provided a locking device which will deter thieves from stealing the microphone. In another embodiment of the invention I have provided a locking mechanism which would offer 50 considerable difficulty to unauthorized removal of the microphone. In the third embodiment of my invention I have provided a locking mecha-

nism which would prevent an unauthorized individual from stealing the microphone unless the microphone was forcibly removed by means of tools.

Modifications of my invention may be made by those skilled in the art and such modifications may be made without departing from the spirit and scope of the invention as set forth in the appended claims.

I claim as my invention:

1. In combination, a standard, a microphone, cooperative plug and jack members on the microphone and standard adapted to electrically connect the microphone to the standard and to support the microphone, and means exterior to the microphone and standard for locking the microphone on the standard. 10

2. In combination, a standard, a microphone, cooperative plug and jack members on the microphone and standard adapted to electrically connect the microphone to the standard and to support the microphone, and threaded means on one of the members adapted to engage the other member to lock the microphone to the standard. 20

3. Means for locking a microphone plug to a standard including threads on the plug and in the standard and a set screw on the standard having an irregular head and a boss for the head, the plug being recessed at one portion thereof to permit the set screw to engage the 30 plug. 25

4. Means for locking a microphone on a standard including a standard lock on one of the members and a lock engaging means on another of the members. 35

5. In combination, a standard, a microphone on the standard, cooperative plug and jack members on the standard and microphone for electrically connecting the two members and supporting the microphone on the standard and rotatable 40 means for manually locking the microphone on the standard. 40

6. In combination, a standard, a microphone, plug and socket members for electrically connecting the microphone and for supporting the 45 microphone on the standard, and additional means exterior to the plug and socket members for locking the microphone on the standard and for additionally supporting the microphone on the standard. 50

EVERETTE M. FOSTER.
